UNITED STATES PATENT OFFICE.

WILLIAM O. HOUSTON, OF BELLAIRE, OHIO.

RECUPERATIVE FURNACE.

1,126,473.

Specification of Letters Patent.

Patented Jan. 26, 1915.

Application filed February 7, 1914. Serial No. 317,301.

To all whom it may concern:

Be it known that I, WILLIAM O. HOUSTON, a citizen of the United States of America, and resident of Bellaire, county of Belmont, 5 and State of Ohio, have invented certain new and useful Improvements in Recuperative Furnaces, of which the following is a specification.

This invention relates broadly to recuperative furnaces, and specifically to a furnace of a muffle type.

The primary object of the invention is to provide a structurally improved muffle furnace, primarily designed for baking enamelled metal ware.

A further object is to provide a furnace of the character mentioned in which the recuperator is so arranged with respect to the combustion chamber and furnace proper that access may be had to either, as for repairs, without disturbing the other and that neither is required to sustain any part of the weight of the other.

As is well known, in ordinary types of recuperative furnaces, the recuperator is located either under or over the combustion chamber. In either case, the falling in of one portion frequently necessitates the tearing out of the other in order to repair the injured portion. Further, the great weight of the portion sustained oftentimes causes a premature collapse of the other portion.

The present invention is directed to a structure wherein the objectionable features noted are obviated.

A still further object of the invention is to provide a furnace which is especially efficient for producing the high temperatures required in enameling furnaces with a minimum of fuel consumption.

With these and other objects in view, the invention resides in the features of construction, arrangement of parts and combinations of elements which will hereinafter be fully described, reference being had to the accompanying drawings, forming a part of this specification, in which—

Figure 1 is a transverse sectional view of an embodiment of my invention; Fig. 2 is 50 a substantially vertical section of the recuperator, taken on the line 2—2, Fig. 1; and Fig. 3 is a horizontal section on the line 3—3, Fig. 2.

Referring to said drawings, in which like 55 designating characters distinguish corre-

sponding parts throughout the several views—I indicates the walls of a muffle which is mounted over the crown 2 of a combustion chamber 3, said muffle being spaced away from the refractory lining 4 of the furnace walls 5 to form a chamber 6 into which the flames from the burning gases in said combustion chamber are directed for wholly enveloping said muffle, whereby an intense heat is imparted to the walls of the muffle and is thereby radiated to the interior of said muffle. Heat is preferably generated within the combustion chamber 3 by means of gas burners placed therein and disposed above the ports 27. From the top of the chamber 6 the waste heat and products of combustion pass outward through a suitably located opening 7 to a passage or passages 8 by which they are conducted to the top of a recuperator, generally designated by the numeral 9, which is located laterally of and is directly connected to one of the side walls 5 of the furnace. The recuperator 9 composes opposite side-walls 10 and an end wall 11, a central division wall 12, and a series of tubes 13, all of which will hereinafter be more fully explained.

The products of combustion which enter the passage or passages 8 pass vertically downward to and through a plurality of flues 14, provided between the adjacent furnace wall 5 and the division wall 12 of the recuperator, to the lower end of said recuperator, thence through horizontal passages 15 to and vertically upward through a plurality of flues 16 and thence outward through the stack 17 which is located over said recuperator. Extending through the opposite side-walls 10 of said recuperator is a plurality of superposed horizontally arranged flues 18 and 19, the flues in each wall being connected to constitute a tortuous descending air passage. The tubes 13 are disposed in superposed relation longitudinally of the recuperator substantially midway between the side-walls 10 of the latter, being directed through the central division wall 12, as is most clearly shown in Fig. 3. Said tubes are so connected at their ends as to form a continuous descending air passage 20. Said tubes are slightly separated and small horizontal passages 21 are provided therebetween affording communication between the flues 14 and between the flues 16, 116

thus permitting the heated products of combustion passing through said flues 14 and 16 to contact with said tubes 13 on all sides.

As is apparent, much of the heat of the products of combustion escaping through the descending flues 14 and ascending flues 16 is absorbed by the tubes 13 and flues 18 and 19 and is thereby imparted to air which is circulated through the air passages afforded by said tubes and flues. Air is admitted to the upper ends of said passages through a horizontal passage 22 which is open to the atmosphere, as shown in Fig. 1, and which communicates with all of said passages, as shown in Fig. 2. As said air passes downward through said tortuous passages, it becomes heated to a high temperature. From said passages the heated air is discharged into a cross-passage 23 from which it is conducted through horizontal flues 24 provided in the bottom of the furnace to ascending flues 25, thence to flues 26 located on opposite sides of the combustion chamber 3, from which it issues into the combustion chamber through a plurality of small ports 27 provided in the side walls of said combustion chamber. Said air enters the combustion chamber in a highly heated condition and thus greatly facilitates the combustion of gases in said chamber, resulting in a material saving in fuel re-

quired to maintain the high temperature of the muffle.

I claim:

The combination with a furnace, of a recuperator, located laterally thereto, said recuperator comprising side walls and a central wall, superposed horizontally disposed flues formed in the side walls, said central wall consisting of a plurality of vertically spaced tubes, vertical flues disposed upon opposite sides of the central wall and connected at their lower ends by passages, a stack communicating with certain of said vertical flues for permitting the products of combustion from the furnace to pass to the atmosphere after passing through the spaces between the tubes of the central wall, said tubes being disposed so as to provide a tortuous passage, an air passage communicating with the uppermost tube for supplying external air to the tortuous passage, and to the flues of the side walls, and means for conducting air from the said flues and tortuous passage to the combustion chamber of the furnace.

In testimony whereof, I affix my signature in presence of two subscribing witnesses.

WILLIAM O. HOUSTON.
